UNITED STATES PATENT OFFICE.

AINSWORTH BUCK, OF SUMMIT, NEW JERSEY.

WINDOW-CLEANER'S ANCHOR.

1,246,538.

Specification of Letters Patent. Patented Nov. 13, 1917.

Application filed April 23, 1917. Serial No. 163,764.

To all whom it may concern:

Be it known that I, AINSWORTH BUCK, a citizen of the United States, and a resident of Summit, in the county of Union and State of New Jersey, have invented certain new and useful Improvements in Window-Cleaners' Anchors, of which the following is a specification.

The invention relates to window cleaners' safety devices, and more particularly to the anchorages therefor, which are attached to or built into the building at the sides of the window openings.

Objects and advantages of the invention will be set forth in part hereinafter, and in part will be obvious herefrom, or may be learned by practice with the invention, the same being attained through the instrumentalities, means and combinations pointed out in the appended claims.

The invention consists in the novel parts, articles, constructions, arrangements, combinations and improvements herein shown and described.

The accompanying drawings herein referred to, and forming a part hereof, illustrate one embodiment of the invention, and taken in connection with the description serve to illustrate the principles thereof.

Of the drawings:

Figure 1 is a fragmentary horizontal section of a device and construction embodying the invention;

Fig. 2 is a fragmentary elevation of the structure shown in Fig. 1; and

Fig. 3 is a perspective of the anchor member alone.

Referring to the accompanying drawings, illustrating by way of example one embodiment of the invention, the wall of a building at the side of a window opening is indicated at 1, the wall being shown of blocks of stone, bricks, or other suitable building material. Into the wall of the building is fitted or built a window frame 2, preferably of metal or other non-combustible material, the window itself being shown at 3, and running in any suitable guides 6 formed on the window frame.

In accordance with certain features of the invention, the anchoring device, to which the safety device worn by the window cleaner is attached while he stands cleaning the window, is not only set between the stones or other blocks of building material, but it

is also anchored or attached directly to the window frame construction.

In the embodied form the anchor device has a face or exterior plate 4, adapted to rest against the wall 1, preferably just at the juncture of the window frame 2 with the wall 1. The plate 4 has projecting therefrom a head 5, over which head a part of the safety device worn by the window cleaner is slipped, in a well-known manner. In the general form of metallic window frame shown, a vertically disposed rod 7 extends from a bottom plate 8 to a top plate 9, which plates are part of the window structure, the rod 7 serving to tie the structure together. In the embodied form, the anchor device is designed to engage the rod 7 to firmly hold the anchor device in position.

In such embodied form, extending backwardly from the plate 4, and preferably integral therewith is the body portion of the anchor, comprising a bar 10, which bar lies in the horizontal joint between two of the stones or bricks, or other constituent members of the wall structure 1. The bar 10 extends or merges into an angled portion 11, which is preferably of greater thickness than the bar 10. From the angled portion 11, and as a continuance of the body of the anchor, a bar 12 extends rearwardly along the side face 15 of the window frame 2. The bar 12 terminates in a hook 16, which hook takes about the rod 7.

As is best seen from Fig. 1, in the present preferred form, the window frame 2 is set into the wall 1. The window frame has, on its outer face, an inwardly shouldered portion 18, and adjoining thereto a laterally extending portion 19, and into the vertically extending recess thus formed, the brick, or stone, or the like, of the building wall 1 fits, preferably the entire length of the frame, to form a solid transverse anchorage for the window frame. The body of the anchor in such preferred form, extends across between the stone blocks, brick, or the like, which fit into the recess 18, 19 of the frame, and the anchor body lies flat against the inner side 15 of the window frame, bringing the strain on the anchor direct onto the window frame. In addition the anchor has its anchorage further strengthened by the engagement of the hook 16 with the rod 7.

It will be seen that the anchor device is

thus firmly and immovably held in position by reason of its attachment to the window frame, and without depending upon any anchorage in the wall itself. It thereby obviates any danger of withdrawal through the disintegration or other failure of the mortar or other material of which the wall may be built. The anchor device is positively and immovably engaged with the window structure, and the building of the wall around it absolutely prevents its removal.

In assembling, the anchorage device is positioned well backwardly, or counterclockwise, from the position shown in Fig. 1, until the nose of the hook 16 is slipped between the wall 15 of the window frame and the rod 7, the hook thereby interlocking with the rod. The anchor device is then swung around in clockwise direction into the position shown in Fig. 1, until the plate 4 is clear of the brick 1. The device is then brought to rest upon the brick of the wall 1 which is below it in Figs. 1 and 2. It may be surrounded with mortar or other binder, and the next brick or block in the wall 1 is laid upon or over the anchor device. It is then held immovably in position by the construction without any danger whatsoever of the device pulling out, as it cannot be dislodged from its anchorage on the window frame without swinging it backwardly, and such a movement is impossible as soon as a stone or brick is laid on top of the anchor. The flat surface of the bar 12 rests against the side 15 of the window frame, and the thick angled portion 11 is located at the corner of the window frame 2 and from this point there is a direct tension along the bar 10.

By the present invention a device is secured which is of simple and strong form, economical of manufacture, which may be rapidly and expeditiously inserted or assembled; and which has a positive and unbreakable attachment or anchorage to the window frame structure itself, it being immovably held in such anchorage by the wall structure thereabout.

It will be understood that the invention possesses other advantages obvious to those skilled in the art, or which may be learned by practice with the invention; and it will be further understood that changes may be made from the precise construction shown and described, without departing from the principles of the invention and without sacrificing its chief advantages.

Copies of this patent may be obtained for five cents each, by addressing the "Commissioner of Patents, Washington, D. C."

What I claim as my invention and desire to secure by Letters Patent is:—

1. In a building construction and in combination a building wall formed with a window opening, a window frame set in the opening, a window cleaner's anchor device with a head at the window opening, and a body extending into the wall between the constituent members of the wall structure and having a lateral arm lying against the rear face of the window frame.

2. A building having a window opening, a window frame therein, a window cleaner's anchor lying in the joint of the wall, and interlocking devices connecting the inner end of the anchor with the side of the window frame within the wall.

3. In a building construction and in combination a building wall formed with a window opening, a window frame set in the opening, a window cleaner's anchor device with a head at the window opening, and a body extending into the wall between the constituent members of the wall structure, and interlocking members on the window frame and on the anchor.

4. In a building construction and in combination a building wall formed with a window opening, a window frame set in the opening, a window cleaner's anchor device with a head at the window opening, and a body extending into the wall between the constituent members of the wall structure and interlocking coöperating members on the anchor and the window frame, respectively, said members engaging and disengaging when the anchor is moved within the wall space but held permanently engaged when the anchor is positioned and built into the wall.

5. A window cleaner's anchor formed of a bar adapted to lie in a masonry joint and formed at its outer end with a head and extended laterally at its inner portion to lie against the rear face of a window frame; said lateral extension terminating in a vertically disposed open hook adapted to interlock with a complementary member on a window frame.

In testimony whereof, I have signed my name to this specification, in the presence of two subscribing witnesses.

AINSWORTH BUCK.

Witnesses:

JOHN D. MORGAN,
LOUISA LOEHR.
